UNITED STATES PATENT OFFICE.

ARTHUR E. RENDLE, OF NEW YORK, N. Y.

GLAZED STRUCTURE.

SPECIFICATION forming part of Letters Patent No. 690,121, dated December 31, 1901.

Application filed October 29, 1900. Serial No. 34,829. (No model.)

To all whom it may concern:

Be it known that I, ARTHUR EDGCUMBE RENDLE, a subject of the Queen of Great Britain, residing at New York city, in the county 5 of New York and State of New York, have invented certain new and useful Improvements in Glazed Structures, of which the following is a specification.

My invention relates particularly to glazed 10 structures of the kind shown in my Patent No. 488,663, of December 27, 1892. In my prior patent I have shown a glazed structure comprising inclined troughs or astragals and cross-troughs constructed and arranged to 15 connect and support the panes of glass at their edges and to receive and carry off all the water accumulating upon the panes or leaking through them at the joints. The troughs or astragals in the glazed structure 20 shown in my prior patent are arranged under the longitudinal joints of the panes of glass, and over the joints are arranged caps, which are secured to horizontal bolts arranged across the astragals by means of vertically- 25 arranged eyebolts. The cross-troughs rest in recesses in the astragals, and each cross-trough is provided with a main gutter and a supplemental gutter. The water which finds its way into the small or supplemental gutter 30 passes into the main gutter through an opening in the bottom of the supplemental gutter. The cross-trough is provided with supports for the adjacent edges of the glass. The supplemental gutter is straight on one 35 side and inclined on the other; but the construction is such as to afford a very serviceable means for collecting water of condensation or water that leaks through the joints and carrying it off to the sides of the structure or to the astragals, which convey it to the edges of the structure. I have found in practice that it is desirable to connect the caps with the astragals by means of a yielding connection in order that the parts may 40 not materially loosen when not used or when the nuts on the bolts slip. I have also found it desirable to provide means for preventing the lower edges of the caps from slipping on the panes while the bolts are being tightened. 45 In my prior patented structure I showed no means for ventilation; but by my present im-

provements I provide for ventilation through the astragals and through the caps.

The cross-troughs in the prior structure at one side of the supplemental gutter are inclined; but it sometimes happens that the gutter becomes so long that the water tends to run over the inclined side of the gutter, and according to my present improvements I so alter this inclined side as to avoid this 55 possibility.

In the prior structure it sometimes happened that moisture or water would creep along the under side of the cross-trough, and in order to avoid this I provide at each end 65 of each section of the cross-trough a flange projecting downwardly, preferably into the inside of the astragals on which the cross-trough rests.

In the accompanying drawings, Figure 1 is 70 a view of a portion of a glass roof constructed in accordance with my present invention. Fig. 2 is a detail view in section, showing the manner of connecting the caps to the astragals and the manner of arranging the cross-troughs. Fig. 3 shows a transverse section on the line 3 3 of Fig. 2. Fig. 4 shows a transverse section on the line 4 4 of Fig. 2. Fig. 5 is a perspective view showing more clearly 75 the shape of the cross-trough and the manner 80 of arranging it.

The inclined troughs or astragals A are usually arranged equal distances apart and extend from the bottom to the top of the inclined roof, and the cross-troughs B, which 85 are preferably made in sections, are arranged at right angles to the troughs A, as shown in Fig. 1. The astragals A may be rectangular in cross-section or U-shaped, as shown in Figs. 3 and 4, or they may be of other suitable shape, and they support on the upper ends of their sides a the panes of glass C, which are symmetrically arranged side by side in the same plane without overlapping edges. The longitudinal edges of the panes 90 are separated, as indicated, and over the intervening space between the panes are located metal caps E, which may be curved, but are preferably of the form shown. These caps are held in place by vertical bolts D, which 100 extend through the interval between the panes of glass C and are connected to curved

or U-shaped strips of metal F, which are secured to the astragals by means of cross-bolts G. A suitable number of bolts D are employed, located at suitable distances apart to securely hold the caps E in place. The curved pieces of metal F form yielding connections between the astragals and the caps E. When the nuts of the bolts D are tightened, the strips F are distended and exert a pressure 10 on the caps, holding them tightly in place, and these curved strips provide such yielding connections that should any of the parts of the structure change positions the caps will be made to automatically compensate for this 15 change and at all times fit the structure tightly.

In the present instance the caps E have their lower edges e turned up to form a double thickness of metal; but this double thickness 20 is comparatively narrow, and there is a tendency for the edges to slip on the glass when coming in direct contact therewith. In order to prevent this, I interpose between the lower edges of the caps and the glass C strips 25 of lead H, which are preferably L-shaped in cross-section, as shown in Fig. 3, one portion of the strip lying on the surface of the glass beneath the edges of the cap, while the other portion projects downward across the edge of 30 the glass toward the troughs or astragals A. These strips of lead H are removable and are held in place only by the caps.

In order to provide for ventilation, openings a' are formed in the sides of the astragals near their upper edges and also in the 35 top of the caps, as indicated at b. Any water entering through the openings b will flow into the bottom of the astragals A, and there is no danger of leakage on this account.

40 The troughs A may be supported on the frame of the roof in any desired way. In order to support the panes at their upper and lower edges and to convey off water which may leak in through the joints or accumulate by condensation on the panes, I employ cross-troughs 45 B, which are preferably made in short sections and supported in recesses a² in the trough or astragals A, as shown in Fig. 5. Each cross-trough is preferably made of sheet metal having a bottom g and sides g' g². The side g² is slightly shorter than the side g', so as to leave a 50 small space between its upper edge and the glass to allow water of condensation to pass into the main gutter or channel x of the trough. The side g' is prolonged by being bent inwardly and downwardly parallel with the 55 outer side of the trough to within a short distance of the bottom g. It is then bent inwardly and carried along parallel to the bottom g and then bent upwardly parallel with 60

the side g', thus forming a supplemental trough or gutter y. The metal is then bent laterally and folded upon itself to form a ledge g³. It is then bent upwardly and laterally to form a support for the adjacent edges of the 65 panes. The upper panes rest on the ledge g³, the lower ones on the ledge g⁴ at the top of the side g'. This pane is also arranged under the lateral projection g⁵. The construction is such as to form a small gutter y, having perforations g⁷, through which the water which finds its way in at the joints passes into the main gutter or channel x and thence into the astragal A. As before stated, the water of condensation passes from the under sides of 70 the pane above the sides g² of the trough into the gutter or channel x. It will be observed by an inspection of the drawings that the cross-troughs are arranged to empty into the inclined troughs and that provision is made 75 for draining off all water that may tend to accumulate either on the upper or lower surfaces of the roof.

In my prior patent above referred to one of the walls of the supplemental troughs y 80 was inclined, and there was a tendency sometimes for the accumulated water to flow out over the top or edge g⁴; but by constructing this trough in the manner shown particularly in Fig. 2 this danger is avoided. In order to 85 prevent water from creeping along the bottom of the troughs to too great an extent, the cross-troughs are formed with flanges J at their ends. Any water creeping along the bottom of the trough will be arrested by these 90 flanges and diverted into the astragals. 95

I claim as my invention—

1. The combination of a series of inclined troughs or astragals, provided with ventilating-openings, panes of glass supported on the 100 upper edges of the sides of the troughs, caps arranged over the adjacent edges of the panes, and having ventilating-openings and yielding connections between the caps and the astragals. 105

2. The combination of a series of inclined troughs or astragals, provided with ventilating-openings near the top of their sides, panes of glass supported on the upper edges of the sides of the troughs, caps arranged over the 110 adjacent edges of the panes and having ventilating-openings in their upper portions, and means for securing the caps in place. 115

In testimony whereof I have hereunto subscribed my name.

ARTHUR E. RENDLE.
